BOTTLE WASHING MACHINE

Archie E. Ladewig and George F. Soelch,
Waukesha, Wis.

Application February 2, 1935, Serial No. 4,662

2 Claims. (Cl. 198—24)

This invention relates in general to improvements in the art of cleansing objects in succession, and relates more specifically to improvements in the construction and operation of machines for automatically washing glass bottles or the like.

A general object of the invention is to provide an improved bottle washing machine which is simple and compact in construction, and which is, moreover, highly efficient in operation.

A more specific object of the invention is to provide improved loading and unloading mechanism for bottle washing machines, which is especially adapted to effect rapid and automatic loading and unloading of the successive bottle carrier pockets in a most effective manner.

Another specific object of the invention is to provide improved mechanism for driving a bottle washing machine and the elements for delivering the successive bottles to and from the carrier pockets of the machine, with minimum danger of breaking the relatively brittle bottles.

Still another specific object of the invention is to provide automatically functioning bottle cleansing structure which may be manufactured and operated at minimum cost, and which may be conveniently actuated by a novice.

An additional specific object of the invention is to provide an improved assemblage for driving a bottle washer, which will function effectively irrespective of variations in the sizes and shapes of the bottles, and which is effectively protected against damage due to possible jamming of bottles.

These and other objects and advantages of the present improvement will be apparent from the following detailed description.

A clear conception of embodiments of the various features constituting the present improvement, and of the mode of constructing and of operating bottle washing machines built in accordance with the invention, may be had by referring to the drawings accompanying and forming a part of this specification, in which like reference characters designate the same or similar parts in the various views.

Fig. 1 is a central vertical section taken longitudinally through the front end of a bottle washer, showing the carrier pocket drive in propelling condition, the loading mechanism in bottle receiving position, and the unloading mechanism in inactive position, the carrier pocket adjacent the driving pawl having been omitted;

Fig. 2 is a similar view of the bottle washer, showing the carrier pocket drive in ineffective

position, the loading mechanism in the act of delivering bottles to the adjacent carrier pockets, and the unloading mechanism in the act of delivering washed bottles from the adjacent carrier pockets;

Fig. 3 is another similar view of the bottle washer, again showing the carrier pocket drive in ineffective position, the loading mechanism in bottle receiving position, and the unloading mechanism in the act of finally discharging a washed bottle;

Fig. 4 is a front end view of the washing machine drawn to a somewhat reduced scale, and showing the carrier pockets diagrammatically;

Fig. 5 is a perspective view of the front end portion of the improved bottle washer;

Fig. 6 is a fragmentary side view of the loading mechanism of the washing machine, showing the safety stop mechanism as it appears during normal operation of the apparatus;

Fig. 7 is a similar view of the safety stop mechanism, showing the same in action; and

Fig. 8 is a front view of the safety stop mechanism of Figs. 6 and 7.

While the improvement has been shown and described herein as being specifically applied to a machine of definite capacity especially adapted to automatically wash a succession of milk bottles, it is not intended to limit the scope of the invention by such specific embodiment since some of the improved features are obviously applicable to other sizes and types of receptacle cleansing machines.

Referring to the drawings, the milk bottle washer illustrated therein comprises in general a main casing 10 having a soaking liquid basin in the lower portion thereof and also having similar endless rails 11 secured to the opposite side walls thereof; an endless conveyor 12 having successive links and rollers 13 cooperable with the rails 11; a succession of bottle receiving and transporting pockets 14 carried by the conveyor 12 and having enlarged open ends adapted to receive the bottles 15; a lower plate 16 disposed within the soaking liquid basin and cooperable with the larger open ends of the pockets 14 to retain the bottles 15 therein when the pockets are inverted; improved mechanism for loading the bottles 15 into the successive empty pockets 14 while at rest; other improved mechanism for removing the washed bottles 15 from the pockets 14, while at rest, and from the machine, at the loading end of the latter; and improved driving mechanism for propelling the

pocket conveyor 12, the loading mechanism, and the unloading mechanism.

The interior of the main casing 10 is, moreover, provided with the usual spray or brush washing mechanism, or both, in addition to the soaking liquid basin, for thoroughly washing the bottles 15, but since this mechanism forms no part of the present improvement, it has not been illustrated herein. The rails 11, conveyor 12, and pockets 14 are likewise of relatively well-known construction, with the exception that the rails 11 have inclined front portions 17 with which the conveyor 12 is cooperable to retain the carrier pockets 14 in substantially parallel, inclined positions as shown in Figs. 1, 2, and 3, during both the loading and the unloading operations, so that both of these operations may be effected closely adjacent to each other and at the same end of the machine with relatively simple and compact mechanisms operable from the main drive which also actuates the conveyor 12.

The improved mechanism for loading the bottles 15 into the successive rows of empty carrier pockets 14 while they are at rest, comprises, a movable trough-like support 18 disposed across the front of the machine between side plates 19; a pair of laterally spaced side arms 20 swingably or tiltably suspending the bottle support 18; a horizontal pivot shaft 21 with which the lower ends of the arms 22 are rigidly connected and which is oscillatable in the side plates 19; a lever 22 for periodically oscillating the shaft 21; a connection 23 for actuating the lever 22; and improved safety stop mechanism cooperable with the admitted bottles 15 for stopping the machine in case a bottle 15 fails to properly enter its receiving pocket 14.

The bottle receiving support 18 is provided with a series of division walls 24 which properly position the dirty bottles 15 disposed thereon, and is secured to the arms 20 by pivots 25 and is adjustable relative to these arms by means of set screws 26, so as to insure proper coaction of the support 18 with the open ends of the bottle receiving pockets 14, during normal operation of the machine. The support 18 is adapted to receive the dirty bottles 15 with their open ends uppermost, as shown in Figs. 1, 3, and 5; and is adapted to be swung toward the receiving pockets 14 and simultaneously tilted so as to deliver the bottles 15 by gravity and in partially inverted condition, into the previously emptied, inclined pockets 14, as shown in Fig. 2, when the conveyor 12 is at rest. The carrier arms 20 are also made adjustable in length so as to insure proper disposition and movement of the support 18, and the actuating lever 22 for the shaft 21 is attached to one of the ends of this shaft beyond the adjacent supporting plate 19, whereas the safety stop mechanism is carried by the other supporting plate 19.

The safety stop mechanism which is shown in detail in Figs. 4, 6, 7, and 8, and also partially in Figs. 1, 2, and 3, comprises a horizontal cross-bar 27 mounted upon the upper ends of longitudinally adjustable rods 28 near the open ends of the pockets 14, so that the bottles 15 delivered by gravity from the inclined support 18 to the inclined receiving pockets 14 will normally pass freely over or above the bar 27; but this bar is so located that if a bottle 15 fails to fully enter its receiving pocket 14, as shown in Fig. 7, the projecting bottle end will strike the bar 27 during subsequent advancement of the conveyor 12. The rods 28 are properly guided by the casing 10, and the lower ends of these rods are pivotally con-

nected to the swinging ends of levers 29, the opposite ends of which are secured to an auxiliary pivot shaft 30 rotatably mounted in the spaced plates 19; and the outer free end of the shaft 30 carries a lever 31, the swinging end of which normally coacts with a notch 32 in a switch actuating arm 33, while the medial portion of this lever is pivotally connected to a rod 34 engaged by a spring 35. The function of the spring 35 is to normally maintain the lever 31 in engagement with the notch 32 of the switch arm 33, but when the cross-bar 27 is engaged by a projecting bottle 15, the shaft 30 is partially rotated so as to swing the end of the lever 31 as shown in Fig. 7, thereby displacing the switch arm 33. The switch arm 33 is swingable about a lower supporting pivot 36 and has its upper swinging end connected to a switch actuating rod 37 in such manner that when the lever 31 is in normal position, as shown in Fig. 6, the control switch 38 for the motor 20 which drives the washing machine is closed; whereas, when the lever 31 is shifted to the position shown in Fig. 7, the switch 38 is open and the operation of the machine is stopped.

The improved mechanism for unloading or for removing the successive clean bottles 15 from the pockets 14 and from the machine is clearly shown in Figs. 1-5, inclusive, and comprises a set of reciprocable bottle ejectors 39 carried by a cross-head 40 movable along inclined guides 41 and along guide slots 42 associated with the opposite side walls of the main casing 10; a bottle receiving and transferring support 43 carried by a horizontal cross-shaft 44 pivotally mounted in the side plates 19; and an auxiliary conveyor 45 movably supported at the upper ends of the side plates 19 and arranged to deliver the finally washed bottles 15 laterally away from the front of the washing machine.

The cross-head 40 has a through shaft 46 which is pivotally connected to one end of an arm 47, the opposite end of which is pivotally attached to a link 48, the extreme lower end of which is pivotally connected to the upper end of the connecting link 23. The upper end of the link 48 is secured to one end of an upper cross-shaft 49 which is journaled in bearings supported on the main casing 10; and an actuating lever 50 is swingably mounted upon the opposite end of the shaft 49 and coacts through a safety spring 51 with a second lever or arm 52 which is rigidly connected to the shaft 49. The upper swinging extremity of the lever 50 carries a roller 53 which is cooperable with a cam 54 carried by the main drive shaft 55; and the assemblage is such that when the shaft 55 revolves, the cam 54, during a minor portion of each revolution, will swing the lever 50 back and forth about the axis of the shaft 49, this motion being normally transmitted through the spring 51 and arm 52 to the rock shaft 49 and from the latter through the link 48 to the bottle ejector and loading mechanism through the arm 47 and connecting link 23, respectively. The bottle loading and ejector mechanisms are actuated only when the conveyor 12 and pockets 14 are at rest, and if either of these mechanisms meets an obstruction which prevents normal operation thereof, the spring 51 will be compressed sufficiently to permit swinging of the lever 50 by the cam 54 upon the shaft 49, without imparting motion to the arm 52, shaft 49, and link 48, thereby avoiding possible damaging of the machine.

The main drive for actuating the conveyor 12 and the washing mechanism, also serves to actu-

ate the bottle delivering support 43 and the discharge conveyor 45; and this drive comprises the main shaft 55; an electric motor 56 drivingly connected to the shaft 55 by gearing 57; a crank 58 rotatable by the drive shaft 55; a pair of oscillatory arms 59 pivotally mounted upon a horizontal shaft 60 carried by the main casing 10; a tie rod 61 interconnecting the swinging ends of the arms 59; and a motion transmitting connection 62 joining the crank 58 and the rod 61.

Each of the arms 59 has a side lug 63 which is engageable, during forward swinging of the arm, with an adjacent pawl 64 suspended from the rod 61, the pawls being engageable with the adjacent conveyor rollers 13 at the ends of the rows of pockets 14, and the throw of the crank 58 being such that the conveyor 12 is advanced by intermittent steps each equal to twice the distance between the successive pocket rows or rollers 13. The arm 59 on the side of the machine adjacent the cam 54 is provided with a knuckle 65 forming a swivel through which a rod 66 extends, and the lower end of this rod is connected to the shaft 44 by means of a lever 67 in such manner that when the arms 59 swing back and forth, the bottle discharge support 43 is simultaneously oscillated. The effective length of the rod 66 is adjustable so as to properly position the support 43, and the upper end of the rod 66 is embraced by a spring 68 which normally transmits the motion of the arms 59 to the rod 66, but which permits relative sliding of the rod 66 within the knuckle 65 in case the support 43 encounter an obstruction, thereby again protecting the mechanism against damage.

The bottle support 43 is again provided with division partitions 69 as in the case of the lower support 18, and the shaft 44 is provided with a weight 70 cooperable with an adjustable stop screw 71, for returning the support 43 from bottle delivery to bottle receiving position. The final discharge conveyor 45 may be driven from any suitable source of power and has a stop plate 72 along the forward edge thereof for confining the washed bottles 15 upon the conveyor 45 when they are righted and discharged from the support 43.

During the normal operation of the improved bottle washing machine, the electric motor 56 is driving the main shaft 55 through the gearing 57, thereby simultaneously revolving the cam 54 and the crank 58. The revolution of the crank 58 is such that the pawls 64 coacting with the rocker arms 59 will advance the successive rows 50 of pockets 14 of the endless series by a step equal to twice the distance between successive rollers 13 during each complete revolution of the crank 58, thereby causing the bottles 15 to travel twice through the soaking and washing zones of the machine before they are finally ejected therefrom. The disposition of the cam 54 relative to the crank arm 58 is such that the loading and ejector mechanisms are actuated only when the conveyor 12 is at rest, so that the pockets 14 55 associated with the inclined front portions 17 of the rolls 11 are stationary during such loading and ejection operations. When the crank arm 58, which moves in a clockwise direction, as indicated in Figs. 1, 2, and 3, moves the pawls 64 rearwardly, these pawls merely ride over the intervening rollers 13 and do not advance the conveyor 12; but when the crank arm 58 moves these pawls 64 forwardly, the pawls drop between two of the successive rollers 13 and there- 60 after immediately engage the forward of these

rollers 13 and advance the pockets 14 as above indicated.

During the period of rest of the conveyor 12, the cam 54 becomes effective to swing the levers 50, 52 and the rock shaft 49, thereby simultaneously transmitting motion through the link 48 to the cross-head 40 and bottle ejectors 39, and to the bottle loading support 18 through the connection 23, lever 22, and carrier arms 20. The dirty bottles 15 may be positioned upon the support 18 with their open ends uppermost, as indicated in Figs. 1 and 3, when the support 18 is at rest; and as this support is carried toward the adjacent inclined row of pockets 14 by the swinging movement of the carrier arms 20, the dirty bottles are partially inverted and are delivered into these inclined carrier pockets 14 by gravity, as clearly indicated in Fig. 2. Simultaneously with this delivery of dirty bottles 15 into the lower row of inclined carrier pockets 14 coacting with the inclined rail portions 17, the ejectors 39 are moved upwardly in an inclined direction from the position shown in Figs. 1 and 3, through the adjacent upper inclined pockets 14, as shown in Fig. 2, thereby positively pushing the finally washed bottles 15 from the upper row of inclined carrier pockets 14 coacting with the rail portions 17. It is to be noted that this ejection of the clean bottles is effected simultaneously with the admission of dirty bottles to the lower inclined pockets, and there is only one row of intervening carrier pockets having preliminarily washed bottles therein, interposed between the loading row and the ejecting row of pockets 14. The loading and ejecting mechanisms may therefore be brought closely adjacent to each other, and the simultaneous loading and ejection of bottles to and from alternate rows of carrier pockets is made possible by the driving mechanism which advances the conveyor by steps equal to twice the distance between the successive pockets 14.

In the event that a dirty bottle fails to properly enter one of the empty receiving pockets 14, and subsequently projects from the pocket as indicated in Fig. 7, the safety stop mechanism illustrated in Figs. 6, 7, and 8 automatically comes into action. The projecting bottle will engage the cross-bar 27, as indicated in Fig. 7, and will exert downward pressure thereagainst. This pressure is transmitted through the rods 28, lever 29, and pivot shaft 30 to the arm 31, and will cause this arm to be moved out of the slot 32 and to actuate the motor control switch 38 through the lever 33 and stem 37. After the obstructing bottle has been removed and the arm 31 is restored to contact with the notch 32, the machine is again ready for normal operation; and this safety stop mechanism prevents possible damage of the loading mechanism during such abnormal conditions.

After a row of clean bottles has been ejected as just described, and a row of dirty bottles has been delivered to the previously emptied row of carrier pockets 14, the conveyor 12 is again advanced to bring the row of previously emptied pockets into position for the reception of dirty bottles. While this advancement is taking place, the rocker arms 59 transmit motion through the rod 66 to the shaft 44 and support 43, thus carrying the support 43 from the position indicated in Figs. 1 and 2 to the position illustrated in Fig. 3. The finally washed bottles 15 are thus simultaneously righted and delivered upon the conveyor 45, and this discharge of the clean bot- 70 75

ties takes place while the conveyor 12 is advancing the carrier pockets 14 one complete step. During the receding operation of the rocker arms 59 and pawls 64, the weight 70 becomes effective 5 to return the support 43 to bottle receiving position, and the spring 68, coacting with the rod 66 prevents possible damaging of the machine in case the movement of the support 43 becomes obstructed. It will also be apparent that the 10 spring 51 acts as a safety feature for protecting the ejectors 39 against possible damage, and these springs 68, 51 cooperate with the safety stop mechanism of Fig. 7 to effectively protect the entire machine against breakage due to abnormal 15 conditions of operation.

From the foregoing description it will be apparent that the present invention provides an improved bottle washing machine which is extremely simple and compact in construction, and 20 which is, moreover, highly efficient in operation. By virtue of the fact that the bottles are transported by steps equal to twice the distance between successive pockets, the loading and ejector mechanisms may be disposed closely adjacent to 25 each other at the same end of the washing unit, and this loading and ejecting of the bottles is, moreover, facilitated by causing the bottle receiving and delivering pockets to coact with a common inclined rail portion 17 and to assume 30 parallel inclined positions during the loading and ejection. The entire operation is automatic, and all mechanisms may be actuated from a common driving source, thereby permitting operation of the machine by a novice and with minimum attention and expenditure of power. The improved machine has proven highly successful in actual 35 commercial operation, both from the standpoint of durability and elimination in breakage of bottles.

40 It should be understood that it is not desired to limit the present invention to the exact details of construction and to the precise mode of operation herein shown and described, for various modifications within the scope of the 45 claims may occur to persons skilled in the art.

It is claimed and desired to secure by Letters Patent:

1. In a bottle washing machine, an endless series of bottle carrier pockets, an endless conveyor movably supporting said pockets, rectilinear guide rails coacting with said conveyor to cause at least three successive pockets at the same end 5 of said series to simultaneously assume parallel similarly inclined positions normal to said guide rails and with their bottle receiving and discharge ends uppermost, means for advancing said conveyor to intermittently advance said pockets, a pusher movable upwardly into said pockets to lift clean bottles upwardly and at an oblique angle out of upper of said inclined pockets while at rest, and a support swingable toward the upper end of lower of said inclined pockets while at rest 15 to tilt and to slide dirty bottles into the receiving pockets by gravity at the same oblique angle and directly beneath the unloading zone, there being but one pocket of said series between the discharging and the bottle receiving pockets. 20

2. In a bottle washing machine, an endless series of an odd number of bottle carrier pockets, an endless conveyor movably supporting said pockets, rectilinear guide rails coacting with said conveyor to cause at least three successive pockets 25 at the same end of said series to simultaneously assume parallel similarly inclined positions normal to said guide rails and with their bottle receiving and discharge ends uppermost, means for advancing said conveyor to intermittently advance said pockets by steps equal to twice the distance between successive pockets, a pusher movable upwardly at an oblique angle into upper of said inclined pockets while at rest to slide clean bottles upwardly and forwardly therefrom, 30 and a support swingable toward the upper end of lower of said inclined pockets while at rest and simultaneously with the pusher movement to tilt and to slide dirty bottles into the receiving pockets by gravity at the same oblique angle and directly beneath the unloading zone, there being 35 but one pocket of said series disposed between the discharging and the bottle receiving pockets. 40
